UNITED STATES PATENT OFFICE.

GILBERT L. CROWELL, JR., OF ARLINGTON, NEW JERSEY, ASSIGNOR TO DOMINICK & HAFF, OF NEW YORK, N. Y.

DESIGN FOR A SUGAR-BOWL, &c.

SPECIFICATION forming part of Design No. 20,667, dated April 7, 1891.

Application filed March 16, 1891. Serial No. 385,330. Term of patent 7 years.

To all whom it may concern:

Be it known that I, GILBERT L. CROWELL, Jr., a citizen of the United States, and a resident of Arlington, in the county of Hudson and State of New Jersey, have invented and produced a new, original, and useful Design for Sugar-Bowls and other Articles of Table-Ware, of which the following is a description, reference being made to the accompanying photograph, which fully illustrates the design as applied to a sugar-bowl.

The body of the article is in general form an oblate spheroid, the lower incurving part of which is divided into sections by the flutes 15 A. The vertical outline of the neck is slightly concave. The ornamentation is that known as "rococo," and it is applied, mainly, to the shoulder of the body and to the flaring edge of the neck. As arranged on the body it is 20 composed of the facing scrolls B, the general curvature of which runs with that of the flutes

A. Between the scrolls may be arranged the flowers C and the shells D, and between the pairs of scrolls the lobed leaves E. The edge of the neck carries a frame-work of scrolls F, 25 which correspond in length to the space between the flutes A and have a sweep harmonizing with the general curvature of the flutes A and scrolls B, thus further suggesting the feature of sectional division. Between the neck-scrolls and the shoulder ornamentation the neck is plain. So also is the body below the shoulder ornamentations.

What is claimed as new is—

The design for sugar-bowls and other like 35 articles of table-ware, substantially as herein shown and described.

GILBERT L. CROWELL, JR.
